Filed July 20, 1970, Ser. No. 24,030

Term of patent 14 years

Int. Cl. D12—11

U.S. Cl. D90—8

The figure is a side perspective of a bicycle frame showing our new design.

The side opposite to the one shown is a mirror image thereof, and the appearance of the rear of the frame is, with the exception of the fork mast, a substantial duplicate of the front.

We claim:

The ornamental design for a bicycle frame, as shown and described.
